UNITED STATES PATENT OFFICE.

ALBERT B. SHULTZ, OF BUFFALO, NEW YORK, ASSIGNOR OF ONE-HALF
TO HERBERT H. HEWITT, OF BUFFALO, NEW YORK.

DESIGN FOR AN AUTOMOBILE ENGINE-HOOD AND SEAT-SUPPORT.

No. 38,044.

Specification for Design.

Patented May 29, 1906.

Application filed April 14, 1906. Serial No. 311,803. Term of patent 14 years.

To all whom it may concern:

Be it known that I, ALBERT B. SHULTZ, a citizen of the United States, residing at Buffalo, in the county of Erie and State of New York, have invented a new, original, and ornamental Design for an Automobile Engine-Hood and Seat-Support, of which the following is a specification, reference being had to the accompanying drawings, forming a part thereof.

Figure 1 is a perspective view, and Figs. 2

and 3 front and rear views, respectively, of an automobile engine-hood and seat-support, showing my new design.

I claim—

The ornamental design for an automobile engine-hood and seat-support, as shown.

ALBERT B. SHULTZ.
